UNITED STATES PATENT OFFICE.

EDGAR F. STINER, OF NEW YORK, N. Y.

HANGING FOR WINDOWS AND THE LIKE.

1,088,042.

Specification of Letters Patent.

Patented Feb. 24, 1914.

Application filed August 5, 1913. Serial No. 783,030.

To all whom it may concern:

Be it known that I, EDGAR F. STINER, a citizen of the United States, residing at New York city, in the county of New York 5 and State of New York, have invented certain new and useful Improvements in Hangings for Windows and the like, of which the following is a specification.

This invention relates to window curtains 10 and the like, and particularly to lace and similar loose-hanging curtains.

The invention consists in a novel form of curtain of this class whereby, among other advantages hereinafter set forth or apparent to those skilled in the art, one fabric piece is adapted to serve for giving a double curtain effect, that is, one effect when seen from one side and another when seen from the opposite side. In hangings for 20 windows, for instance, it is now customary to produce the double curtain-effect by two hangings suspended from two poles, one such hanging being a single curtain extending undivided from side to side of the window frame and the other two curtains draped back.

In the accompanying drawings, illustrative of the present invention, Figures 1 and 2 are elevations of two forms of the improved hanging as seen when veiling a window or the like; Figs. 3 and 4 are central vertical sectional views of the hangings shown in Figs. 1 and 2, respectively; and, Figs. 5 and 6 show the hangings of Figs. 1 35 and 2, respectively, extended.

According to this invention, in place of weaving or otherwise forming two distinct hangings for each window or the like, one piece *a* of fabric is woven or otherwise 40 formed. The length of this piece is approximately double that which would be required for a single hanging. Such piece is further formed with a split *b* extending from one end thereof (Figs. 1, 3 and 5) or 45 from each end thereof (Figs. 2, 4 and 6), toward the middle of the piece. The extent to which the split extends is limited. That is to say, intermediate the ends of the piece, *i. e.*, substantially centrally thereof, is a field 50 or section *c*, of suitable dimension, as hereinafter indicated, lengthwise of the piece, that is continuous or unbifurcated clear across the piece. In the present instance (either of the forms shown) the margins of 55 this field or section which adjoin the ends of

the piece are the scallopings *d* representing a part of the lace or other design or ornamentation of the hanging. With a hanging thus formed it is thrown over a pole *e* or the like support, as shown in the first four figures of the drawing, and its ends treated in some way to give the effect of a double hanging. That is to say, if the hanging is of the form shown in Figs. 1, 3 and 5, the bifurcated end is allowed to hang as it will, 60 either end in the case of a window, for instance, being "outside" as taste or style may dictate; if the hanging is of the form shown in Figs. 2, 4 and 6, one or both of the two bifurcated ends may be draped back. 65 A hanging thus formed obviously considerably reduces the cost of manufacture. It also avoids the necessity for two poles and by requiring only one pole gives greater range to the decorator in arranging the 70 hangings for a room to the best advantage and with a view to produce a graceful and artistic effect. It has the further important advantage that the one hanging may be suited to different windows or the like, although they may vary in depth. That is 75 to say, the decorator has only to adjust the end of the hanging that is to hang "straight" or undraped so that it suits the depth of the particular window being treated and 80 then take care of any disparity in shortage or superfluity of length in the other end by draping its members or parts to suit the hanging to a window of any depth, within 85 reasonable limits. In such adjustment the 90 pole would cross the field *c*, or, otherwise stated, the fold *f* (Figs. 3 and 4) incidental to suspending the hanging from the pole in the way stated would cross such field, more or less near one of the margins thereof 95 aforesaid, as the case might be.

I have shown in the drawings a hanging made of lace or the like. But it is obvious that the material thereof and whether or not it possesses ornamentation are immaterial. 100

Having thus fully described my invention, what I claim as new and desire to secure by Letters Patent is:—

1. A loose-hanging double curtain consisting of an intact elongated piece of suitable fabric having a transverse section thereof half-way between its ends and across the piece adapted to be folded over a curtain pole and having one of its end portions bifurcated longitudinally from the extrem- 105 110

ity thereof to said section, said section being continuous from one lateral edge of the piece to the other.

2. A loose-hanging double curtain consisting of an intact elongated piece of suitable fabric having a transverse section thereof half-way between its ends and across the piece adapted to be folded over a curtain pole and having each of its end portions bifurcated longitudinally from the extremity

thereof to said section, said section being continuous from one lateral edge of the piece to the other.

In testimony whereof I affix my signature in presence of two witnesses.

EDGAR F. STINER.
